COMBINED ACCOUNTING MACHINE AND
TYPEWRITER

Arthur J. Moellenbeck, Milwaukee, and Howard G. Stauffer, Wauwatosa, Wis., assignors to The National Cash Register Company, Dayton, Ohio, a corporation of Maryland

Application November 6, 1943, Serial No. 509,233

4 Claims. (Cl. 235—60.12)

1

2

This invention relates to adding and listing machines commonly known as accounting or bookkeeping machines, and more particularly to the type of machine having a complete typewriting mechanism associated with the adding and listing mechanism. Such type of combined adding machine and typewriter is particularly illustrated in United States Letters Patent No. 1,197,276, issued to Halcolm Ellis on September 5, 1916.

More specifically, this invention relates to novel means for taking automatic totals and/or sub-totals in combination with several interlocking control devices for preventing the taking of the automatic totals and/or sub-totals during certain specific types of operations.

The following United States Letters Patent, showing various features of a combined adding machine and typewriter of the type shown in the above-mentioned Ellis patent, will be more specifically referred to as the occasion requires during the specification. These patents are United States Letters Patent to Frederick W. Bernau, No. 1,601,102 and No. 1,670,018, dated September 28, 1926, and May 15, 1928, respectively; Emil J. Ens, No. 1,819,084, dated August 18, 1931; Raymond A. Christian, No. 1,939,804, dated December 19, 1933; Charles L. Lee, No. 2,079,355, dated May 4, 1937; Raymond A. Christian, No. 2,032,098, dated June 1, 1937; and Jesse R. Ganger, No. 2,217,221, dated October 8, 1940.

One of the objects of this invention is to provide novel means whereby the condition of the accumulator will be printed automatically when the traveling carriage is tabulated to a predetermined or selected position.

Another object of this invention is to provide novel means for electromagnetically depressing the total key to take an automatic total when the traveling carriage has been tabulated to a selected or predetermined position.

Another object of this invention is to provide novel means for automatically taking totals and/or sub-totals when the traveling carriage has been tabulated to predetermined or selected positions.

Another object of this invention is to provide novel means in a combined typewriting and adding machine for automatically taking totals and/or sub-totals, after the carriage has been tabulated to a predetermined position, in combination with means for preventing said automatic total from being taken when the accumulator is in a negative condition.

A further object of this invention is the pro-

vision of means for taking automatic totals and/or sub-totals when the traveling carriage is in a predetermined position, in combination with means for preventing said automatic total from being taken when said traveling carriage has been moved into said predetermined position under control of the typewriting mechanism.

A still further object of this invention is the provision of means for taking automatic totals when the traveling carriage is in a predetermined position, in combination with means for preventing said automatic total from being taken while the carriage is moving into said position.

A further object of this invention is to provide means for taking automatic totals when the traveling carriage is in a predetermined position, in combination with means for preventing the taking of such totals during the operation of the carriage return mechanism.

Another object of this invention is the provision of novel means for taking automatic totals when the carriage is in a predetermined or selected position, in combination with means for preventing the taking of such totals during the time the machine is being operated to accumulate in the accumulator.

More specifically, it is an object of this invention to provide a novel automatic electromagnetically operated means for taking totals and/or sub-totals when the traveling carriage is in a predetermined position, in combination with a plurality of switches arranged in circuit with the electromagnetic means to prevent operation of said electromagnetic means during certain types of operations of the machine.

A further specific object of this invention is the provision of novel electromagnetic means for automatically taking totals and/or sub-totals when the traveling carriage is in a predetermined position, in combination with a plurality of switches in circuit with said electromagnetic means to prevent said electromagnetic means from taking the automatic total and/or sub-total during certain types of movement of the traveling carriage and of the machine.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a right side elevation of a portion of

the machine, showing the electromagnetic means for depressing the total key, a part of the electric drive mechanism for the machine, and also a portion of the totalizer mechanism.

Fig. 2 shows a portion of the traveling carriage stop bar and the hanging bar lever for controlling the total key lock.

Fig. 3 is a plan view of the electromagnetic means, partially broken away, for automatically depressing the total key.

Fig. 4 is a wiring diagram showing the electromagnet and the switches in circuit therewith.

Fig. 5 is a detail view, partially broken away, showing the total key, the lock therefor, and the means under control of the hanging bar lever for releasing the lock from the total key.

Fig. 6 is a side elevation showing the traveling carriage in general, the sub-total key and the means operated by the traveling carriage for depressing the sub-total key, and also a portion of the typewriting mechanism and carriage return mechanism.

Fig. 7 is a detail view showing a portion of the typewriter escapement mechanism and a portion of the carriage tabulating mechanism.

Fig. 8 is a front elevation showing the means on the traveling carriage for depressing the sub-total key.

Fig. 9 is a detail front elevation of a part of the mechanism for initiating the carriage return movement.

Fig. 10 is a rear elevation, partially broken away, showing a part of the carriage return mechanism and one of the control switches controlled thereby.

Fig. 12 is a sectional detail view through a portion of the mechanism shown in Fig. 7.

Fig. 13 is a detail view of the part of the mechanism shown in Fig. 11.

GENERAL DESCRIPTION

Described in general terms, the invention herein includes an electromagnetic means for automatically taking totals and/or sub-totals from an accumulator in a machine of the type shown and described in the above-mentioned Ens Patent No. 1,819,084.

Machines of the type disclosed in the Ens patent and other patents mentioned herein are provided with a traveling carriage having means thereon for controlling various functions of the machine, such as column selection through tabulating mechanisms, so that, when the carriage is in a predetermined or selected position, totals may be taken of the machine, or sub-totals may be taken of the machine. Many improvements have been made in machines of this type, such as the inclusion of overdraft or negative total-taking mechanism, and the present invention is in connection with a machine having an overdraft mechanism such as that disclosed in the above-mentioned Lee Patent No. 2,079,355.

Also, automatic carriage return mechanism has been added to machines of the type shown in the Ellis Patent No. 1,197,276, such as that shown in the Bernau Patent No. 1,670,018 and also in the Ganger Patent No. 2,217,221.

As stated above, the invention broadly includes electromagnetic means for automatically taking totals and/or sub-totals from the accumulator when the carriage is in a predetermined position. Means is also provided for preventing the auto-

matic total-taking even though the carriage is in said predetermined position, if the accumulator shows or has a negative amount therein, such as an overdraft. Other means is provided for preventing the taking of a total or a sub-total during the time the machine is being operated to add or accumulate in the accumulator. Such means includes one of several switches which are arranged in a series circuit with the electromagnetic means, which switch is normally closed, but, when the machine is being operated to add, the switch is automatically opened, thus breaking the circuit to the electromagnet. Also, when the overdraft key has been released, due to the fact that the accumulator shows an overdraft, this same switch is opened for the same purpose of breaking the circuit to the electromagnetic means.

There is also means provided in the form of another switch in circuit with the electromagnetic means, which switch is normally closed but which is adapted to be opened while the carriage is being tabulated to the above-mentioned predetermined total-taking position.

Another feature of the present invention is another switch, also in series circuit with the electromagnetic means, for preventing an operation of the electromagnet during the time the carriage is being returned from any typewriting or tabulated position to its normal right-hand position.

The invention also includes means for controlling the lock for the total key, which is normally effective to prevent that lock from being released when the traveling carriage is moved into said predetermined total position by the typewriting mechanism during the typing of any information or data in connection with any transaction which is being recorded by the recording and printing mechanism of the machine.

Another switch, normally open, is also in series circuit with the electromagnetic means, which switch is adapted to be closed when the traveling carriage reaches the predetermined position after having been tabulated to that position, so that the electromagnet will be energized to automatically depress the total key when all of the other above-mentioned switches, which are in this same series circuit, are closed.

All of the details of the above switches and controlling devices will be described in detail in the detailed description which follows.

DETAILED DESCRIPTION

55 Main operating mechanism and adding and totalizing mechanisms

The mechanism of the machine embodying the present invention is supported between a pair of side frames 60 and 61 (Fig. 1), which are secured to and carried by a base 62. Enclosing the mechanism of the machine is a case 63 (partially shown in Figs. 6, 7, and 8), which case is also secured to the base 62.

The accounting machine mechanism is operated by a conventional type of motor, either of the start-stop type shown in United States Letters Patent to Charles H. Arnold, No. 2,142,341, dated January 3, 1939, or of the conventional type of constantly running motor, such as that shown in the above-mentioned Bernau Patent No. 1,601,102. Either of said types of motors, as is shown in the two patents just mentioned, is adapted to operate a link 65 (Fig. 1), which is pivoted to an operating arm 66 fast on a main drive shaft 67, which operates the mechanism

of the machine. The link 65 is adapted to be raised and lowered, thus rocking the arm 66 and consequently the shaft 67 first counter-clockwise and then clockwise to operate the machine.

The usual and well-known totalizer elements 70 and adding racks 71 (Fig. 1) are provided to accumulate amounts set up on a keyboard. As is well known, totals and sub-totals can be taken of the amounts accumulated on the totalizer elements 70 at any desired intervals. The invention disclosed herein relates to the operation of the total and/or sub-total keys to take totals or sub-totals, and therefore there is no illustration or description of the accumulating mechanism as far as the transfer is concerned intermediate the various denominational elements of the accumulator, nor is there shown or described any of the mechanism for engaging and disengaging the totalizer with the racks at the various times necessary for total, sub-total, and adding operations. However, such mechanism is fully illustrated and described in the above-mentioned Ens patent, and reference may be had thereto for a description of that mechanism.

Totals are taken from the totalizer elements 70 in this type of machine under the control of a total key 75 (Figs. 1, 5, and 8). When this total key 75 is depressed, the mechanism shown and described in the above-mentioned Ens patent engages the totalizer elements 70 with the racks 71 at such time that the racks 71 will clear the totalizer elements 70 of any amount that is stored therein, so that the same may be printed by printing mechanism to be described hereinafter.

Such machines are also usually provided with a sub-total key to permit the taking of a sub-total or sub-balance, which, as is well known in the art, includes the clearing of the totalizer elements 70 by the racks 71, printing that amount, and then causing said racks 71 to again add that total back into the totalizer elements. Such sub-total mechanism is also fully illustrated and described in the above-mentioned Ens patent. However, in the present application a sub-total key 76 is shown in Figs. 6 and 8, to be automatically depressed by means to be described hereinafter, so that sub-totals may be automatically taken as well as totals.

In accounting machines of the type in which the present invention is involved, and particularly when certain machines are used in banking institutions, the totalizer elements are often in a negative condition, due to the fact that a greater amount has been subtracted therefrom than has been added thereto. This negative amount, known in the art as an overdraft, may be printed by machines of this type by the means which is fully illustrated and described in the above-mentioned Lee Patent No. 2,079,355. In the present invention, however, only a very small portion of that mechanism is herein shown, and this will now be described. An overdraft key 77 is shown in Fig. 1 and is normally latched in its undepressed position by a latch 78, to which is pivoted a link 79 in turn connected to an arm 80 secured to a shaft 81, known in the art in connection with this type of machine as the overdraft shaft. This shaft 81 is adapted, by mechanism fully illustrated and described in the above-mentioned Lee patent, to be rocked in a clockwise direction whenever the totalizer elements 70 are in a negative or overdrawn condition, and, when this shaft 81 is so rocked in a clockwise direction, the link 79 rocks the latch 78 to release it from a shoulder 82 on the overdraft key

77, thus permitting depression of the overdraft key 77 when the totalizer elements 70 are in a negative or overdrawn condition. This key 77, at the end of such operations, is returned to its normal position by a spring 83.

Printing mechanism

Only a small portion of the printing mechanism is shown in this application, and, for a further and fuller description thereof, reference may be had to the above-mentioned Ellis patent. Connected to the actuating rack 71 (Fig. 1) by a pin-and-slot connection 90 is a lever 91 pivoted at 92. Pivoted to the lever 91 is a link 93, which in turn is pivoted to a type segment 94, which cooperates with a platen 95 carried by a traveling carriage to be described hereinafter.

From the above description it is clear that the differential movement of the rack 71, through the pin-and-slot connection 90, is transmitted to the type segment 94, so that the amount which has been taken from the totalizer and set up on the rack 71 is transmitted differentially to the type segment 94, so that it may be printed on a printing medium around the platen 95.

Traveling carriage

A traveling carriage 100 (Figs. 6, 7, and 10) is supported at its rear side for horizontal movement on the case 63 by means of a lower ball-race 101 secured to the case 63, an upper ball-race 102 secured to the frame of the traveling carriage 100, and a plurality of ball bearings 103 interposed between the ball-races 101 and 102. The front of the traveling carriage 100 is supported by means of rollers, which bear on the top surface of a guide rail 104 secured to the case 63. The traveling carriage 100 is prevented from tipping up in front by means of rollers 105 cooperating with the bottom surface of the rail 104. Brackets 106, secured to the carriage 100, cooperate with undercut portions of the ball-race 101 to prevent the carriage from being tilted upwardly at the rear side. The carriage 100 supports the platen 95, previously described, so that the platen may be rotated for line-spacing and shifted laterally with reference to the machine, along with the carriages 109.

The traveling carriage carries the usual stop bar 107 on the front portion thereof, which, as is well known in the art, is for the purpose of having adjustably mounted thereon stops of various types for controlling the various functions of the machine.

Mounted on this stop bar 107 is a pair of blocks 108 (Figs. 6 and 8) carrying a cam arm 109 cooperating with a roller 110 carried by a bell crank 111 pivoted at 112 to a bracket 113 secured to the case 63. The bell crank has a flange 114, which lies directly above the sub-total key 76, with the result that, when the traveling carriage is moving in either direction, the cam arm 109, by its contact with the roller 110, operates the bell crank 111 to depress the sub-total key so that a sub-total may be taken from the accumulator wheels 70 when the total key 75 is automatically depressed by means to be described hereinafter.

It will be understood that in machines of this type it requires the depression of the sub-total key 76, along with the depression of the total key 75, in order to take a sub-total or sub-balance from the totalizer wheels 70, as fully described in said Ens patent.

The cam arm 109 is so located on the carriage that the sub-total key 76 is depressed just before the carriage reaches the sub-total columnar po-

sition, while moving in tabulating direction. Therefore, when the carriage reaches the sub-total position, the cam arm 109 is beyond the roller 110 on the bell crank 111. The usual latch means, shown and described in the above-mentioned Eins patent, latches the sub-total key 76 in operated position until released during the machine operation.

It should be here noted that the sub-total key 76 is depressed by cam arm 109 whenever the carriage moves the cam arm 109 over the roller 110, and this occurs in tabulating, return, and letter-space movements of the carriage. However, the sub-total key has no control over the functions of the machine, other than controlling the time of release of the total key 75. Therefore, when the sub-total key 76 is depressed, without depressing the total key 75, no control is effected by the sub-total key, and depression thereof is an idle operation. When the sub-total key is depressed for such an idle operation, it is released during the operation of the accounting machine in the usual manner by mechanism shown and described in said Eins patent.

The traveling carriage 100 is also provided with the usual carriage return mechanism, which will now be briefly described. This return mechanism is substantially of the same principle of operation as that shown in the above-mentioned Bernau Patent No. 1,670,018 and is also like that shown in the Christian Patent No. 2,082,098.

This carriage return mechanism, of course, is for the purpose of returning the carriage back to its extreme right-hand position after certain types of operations have been accomplished by the machine. This carriage return mechanism may be operated or started automatically, or it may be operated by moving the carriage to the left manually until the mechanism which sets off the carriage return mechanism or initiates its movement is contacted, whereupon it is connected to the driving motor of the machine to return the carriage automatically to its extreme right-hand position.

On the rear of the carriage 100 there is mounted the usual rack 115, which meshes with a pinion 116. This pinion carries clutch teeth 117 adapted to be moved upwardly into cooperation with an operating or return clutch 118, which is driven by means connected to the motor which drives the operating mechanism of the machine. This operating motor (not shown herein) is adapted to be started by means of a mercury switch 119 (Figs. 6 and 10), which is secured to a block 120 adapted to be rocked when the pinion 116 is raised to engage its teeth 117 with the clutch 118.

When the mercury switch 119 is tilted, it completes the circuit to the electric motor to cause it to drive the clutch 118 to cause the raised pinion 116, through the rack 115, to automatically return the carriage 100 to its extreme right-hand position upon engagement of a stop 121 (Fig. 9), carried on the stop bar 107, with a finger of a sliding bar 122 (Figs. 6 and 9) mounted in the case 63. This bar 122 is connected by a bell crank 123 to a vertical rod or link 124, the lower end of which surrounds the forward end of a lever 125 pivoted at 126 to the case 63. The rear end of the lever 125 (Figs. 6 and 10) engages a lever 127 pivoted at 128 on the case 63. The other end of the lever 127 is connected by a spring 129 to a lever 130, which also engages a grooved hub of the pinion 116. Another arm 131 of the lever 130 carries the block 120. When the carriage is

5 moved to the left, so that the stop 121 (Fig. 9) engages the finger at the left of the bar 122, said bar 122 is moved toward the left (Fig. 9) and, through the bell crank 123, depresses the rod 124, thus rocking the lever 125 counter-clockwise (Fig. 6), which rocks the lever 127 (Fig. 10) in a clockwise direction, whereupon the spring 129, acting as a link, rocks the lever 130 counter-clockwise. This movement of the lever 130 rocks the mercury switch, which closes the circuit to the motor, thus starting to drive the clutch 118, and, as the lever 130 continues in its counter-clockwise movement, the pinion 116 is raised and the clutch 118 engages the teeth 117 of the pinion 116, whereupon the carriage 100 is returned to its extreme right-hand or normal position. This direction, as viewed in Fig. 10, is toward the left.

10 The pinion 116 and the clutch 118 are mounted in what is known as a carriage return head 132, which is supported on the case 63.

20 Automatic depression of total key

As stated previously, the total key 75 is adapted to be automatically depressed when the traveling carriage 100 has reached a predetermined or selected position, in which position it is desirable to print the total or balance from the totalizer elements 10. The means for accomplishing such depression of the total key 75 includes a normally inactive electromagnetic means adapted to be rendered active by having the circuit there-through closed when the traveling carriage 100 has reached a predetermined position. Also in circuit with the electromagnet and said switch are four other switches, all of which have to be closed in order to energize the electromagnet to render it active. These switches and the means for controlling them will be described hereinafter.

25 Fig. 4 shows a wiring diagram of the circuit for the electromagnetic means and includes in that circuit the above-mentioned switches. This circuit is as follows: from the positive side of a supply line 148 through a fuse 141 to a manually-operable snap switch 142 mounted on the case 63 (Fig. 6), through a switch 143 (Fig. 1) controlled by the machine operating mechanism and also by the overdraft key releasing mechanism, through a switch 144 (Fig. 7) controlled by the carriage tabulating mechanism, then through a switch 145 (Fig. 10) controlled by the carriage return mechanism, and thence through a switch 146 (Figs. 6 and 10), which is normally opened but is adapted to be closed by a block 147 mounted 30 on the traveling carriage 100 and in the total position thereof, and also by a block 148 mounted on the traveling carriage 100 in the sub-total position thereof. When the switch 146 has been closed either by the block 147 or by the block 148, the circuit continues through an electromagnet 149 and from the electromagnet 149 to the minus side 150 of the supply line.

35 The electromagnet 149 (Figs. 1 and 3) is mounted on a plate 151 secured to the bottom of the base 62. Pivoted to a core 152 of the electromagnet 149 is a link 153, which is also pivoted on a stud 154 secured to the base 62. Pivoted to the link 153 is a link 155, which in turn is pivoted to a bell crank 156 mounted on a stud 157 carried by a bracket 158 secured to the base 62 by means of screws 159. The bell crank 156 carries a stud 160 having an annular groove in which a loop 161 of a wire or link 162 operates. The upper end of the link 162 is connected to the lower end of the total key 75. The loop 161 permits manual de-

pression of the total key 75 independently of the electromagnet 149.

When all of the switches 142, 143, 144, 145, and 146, shown in the wiring diagram of Fig. 4, are closed, the electromagnet 149 is energized, whereupon the core 152 is moved toward the left and the link 155 rocks the bell crank 156 (Fig. 1) counter-clockwise, whereupon the link 162 lowers or depresses the total key 75.

As stated above, this occurs when the traveling carriage 100 is in one of a plurality of predetermined positions. One of these positions is the total position, in which the total is printed from the totalizer elements 70, and another is the sub-total position, in which the sub-total is printed from the totalizer elements 70. The block 147 (Fig. 10) controls the switch 146 to close the same when the carriage 100 is in the total columnar position, and the block 148 closes the switch 146 when the carriage 100 is in the sub-total columnar position.

The total key 75 is normally locked or held against depression at all times except when the carriage 100 is in the total or sub-total position. Such positions are determined by a preset stop 168 (Fig. 2), which determines the total columnar position of the carriage 100, and a preset stop 169, which controls the sub-total columnar position of the carriage 100.

When the carriage 100 is in either of said two columnar positions, the lock for the total key is released from the total key, so that it may be automatically depressed by the electromagnet 149 in the manner previously described.

When the carriage 100 is in the total columnar position, the stop 168 (Fig. 2) contacts the top of an upturned finger 170 of a lever 171 pivoted on a stud 172 mounted on a cross frame 173 (Fig. 11), which is carried by the side frames 60 and 61. The stop 168 depresses the lever 171—that is, rocks it clockwise—whereupon its left end raises a link 174 (Figs. 2 and 5) having a stud 175 connected by a spring 176 to a stud 177 on a link 178, thus raising the link 178 when the right end of the lever 171 is depressed by the stop 168. The link 178 carries a pin 179 engaged by a slot in the lever 180 pivoted on a stud 181 carried by the left side frame 61. A flange 182 of a lever 183 pivoted on the stud 181 is held against the under left side of the lever 180 by a spring 184. Pivoted to the lever 183 is a latch link 185, the forward end of which is slotted to ride on a stud 186 carried by the left side frame 61. The link 185 has a latch finger 187 engaging a notch 188 in the total key 75.

When the lever 171 is rocked clockwise as viewed in Fig. 2 by the stop 168 in the manner described above, to raise the link 178, the pin 179 rocks the lever 180 counter-clockwise, whereupon it, through the lever 183, moves the link 185 to the right (Figs. 1 and 5) and withdraws the latching finger 187 from the notch 188 of the total key, thus conditioning the total key for depression by the electromagnet 149 when the carriage 100 has been tabulated to the total columnar position as designated by the carriage stop 168.

When the carriage stop 168 moves off the finger 170 of the lever 171, the spring 184 rocks the lever 183 clockwise and moves the finger 187 back against the side of the key 75, so that, when it is restored near the end of the operation, the finger 187 will again engage the notch 188 and lock the total key 75 against depression. After the key 75 has been depressed, the lever 183, by its contact with the lever 180, will pull down on the link 75

178, thus lowering the left end of the lever 171, moving it into its normal position, whereupon the finger 170 will again be in position to be contacted by the total stop 168 or the sub-total stop 169.

When the sub-total stop 169 is moved into the sub-total columnar position, wherein this stop 169 contacts the top of the finger 170, the latch finger 187 (Fig. 5) is withdrawn from the total key 75 in a manner identical with that just described in connection with the total stop 168, so that in taking sub-totals, when the sub-total key 75 is depressed by the cam arm 109 on the carriage, as previously described, the electromagnet 149 can depress the total key 75 to complete the operation of taking a sub-total.

Tabulating control of electromagnet

When the machine is being tabulated to any of its columnar positions, it is very essential that the total key 75 be not depressed during the tabulating movement of the carriage; therefore it is necessary to open the switch 144 (Figs. 4 and 7), so that, if the carriage is tabulated into a position whereby either of the stops 168 or 169 (Fig. 2) passes over the lever 171, the closing of the switch 146 (Figs. 4 and 6) will have no effect—that is, it will not complete the circuit to the electromagnet 149—because of the fact that the switch 144 under control of the tabulating mechanism has been opened upon the initial movement of the carriage during the tabulating thereof. As is fully described, the tabulating movement of the carriage in the above-mentioned Christian Patent No. 2,082,098 is started by the downward movement of a tabulating bar 190 (Fig. 11), which rocks a lever 191 counter-clockwise. This lever 191 is pivoted on the frame 173. The lever 191 cooperates with the lever 192 pivoted on a stud 193 secured to the frame 173. The lever 192 has a surface 194 (Fig. 13), which cooperates with a stud 195 (Fig. 11) in an escapement control plunger 196 supported for vertical sliding movement in a groove in the frame 173. A spring 197 is tensioned to urge the lever 192 counter-clockwise to normally maintain an upper raised portion 198 thereof in contact with the lower surface of a lug 199 on the frame 173. This lug 199 is slotted to form a slide for the plunger 196. The lever 192 carries a stud 200, which extends through a slot 201 in a tabulating stop bar 202, the upper end of which is loosely supported in a vertical groove in the tabulating frame 173. The right edge of the bar 202, as observed in Figs. 11 and 13, cooperates with a rounded projection 203 of a latch 204 pivoted to the frame 173. A torsion spring 205 urges the latch 204 clockwise into contact with a stud 206 carried by the lever 192. A torsion spring 207 cooperates with a stud 208 in the bar 202 to urge said bar upwardly to normally maintain the lower end of the slot 201 in contact with the stud 200. Pivoted on the stud 193 is a lever 209 having an enlarged portion 210 cooperating with the stud 195 in the plunger 196. A torsion spring 211 urges the lever 209 counterclockwise to normally maintain an upwardly extending portion 212 thereof in contact with the lower surface of the lug 199. A stud 214 normally connects the lever 209 to an escapement control bar 215 supported in the same vertical groove as the bar 202 and urged counter-clockwise by a spring 216. The stud 208 in the bar 202 extends through an opening 217 in the bar 215. The bar 215 has a recess 218 with a notch 219 therein, which cooperates with a square

stud 226 in a stop pawl 221 held in contact with a stud 222 by a spring 223.

The downward movement of the tabulating bar or lever 199, effected either manually or by means of tabulating keys, or automatically by means illustrated and described in the above-mentioned Christian Patent No. 2,082,098, rocks the lever 191 counter-clockwise, which imparts a clockwise movement to the lever 192, whereupon the spring 287, in cooperation with the stud 298, lifts the bar 292 upwardly until its upper end is in the path of a tabulating stop 224 carried by the stop bar 197. The latch 204, influenced by the spring 205, hooks under the stud 206 to retain the lever 192 in its moved position.

The bar 215 is raised by stud 208 when the bar 202 is raised, and the latch 204 moves both bars 215 and 202 toward the left, causing them to be latched in their upward positions by the shoulder of the notch 219 snapping over the square stud 229.

The clockwise movement of the levers 192 and 209 through their engagement with the stud 195 moves the bar 196 downwardly. Projecting into an opening near the bottom of this bar 196 is the end of a bell crank 230 (Figs. 7 and 11), which is pivoted on a stud 231 of a bracket 232 secured to the lug 199 of the frame 173. A spring 233, which normally holds the bar 196 in its upward position, shown in Fig. 11, is stretched and put under tension upon the downward movement of the bar 196 by the levers 192 and 209. Pivoted to this bell crank 230 is a link 234, which is pivoted to a lever 235 pivoted at 236 to a lug (not shown) of a top frame 237, which is secured to the side frames 60 and 61. A link 238 connects the lever 235 with an arm 239 pivoted on a stud 240 mounted in a portion (not shown) of the top frame 237. A yoke 241 connects the arm 239 with an arm 242, which contacts and rocks an escapement retaining pawl 243 (Figs. 7 and 12) away from an escapement ratchet 244, which is secured to a shaft 245, which also has secured thereto a pinion 246 meshing with a rack 247 on the traveling carriage 100.

As the link 234 is moved toward the left (Fig. 7) in the manner previously described, the lever 235, the link 238, and the arms 239 and 242 disengage the pawl 243 from the ratchet 244 to permit a free movement of the pinion 246 by the rack 247 on the traveling carriage 100 during the tabulating movement of the carriage.

Pivoted to the lever 235 is a link 250, which is also pivoted to the lower end of an arm 251 pivoted on a stud 252 supported by the case 63. This arm 251 carries one prong of the switch 144, and consequently, when the tabulating movement of the carriage 100 is initiated by the depression of the tabulating lever 190 and the link 234 is moved toward the left as viewed in Fig. 7, upon such movement of the tabulating lever 190, the link 250 is moved to the left, which rocks the arm 251 clockwise, thus opening the switch 144 so that the circuit to the electromagnet 149 is broken by the opening of the switch 144 during the tabulating movement.

When the stop 224 (Fig. 11) strikes the bar 202, the bar 202 is pushed downwardly in the manner described in the above-mentioned Christian Patent No. 2,082,098, and, as the carriage rebounds in the usual manner—that is, when it backs up slightly or the stop 224 moves slightly to the left and then comes back to its stopping position, when it reaches said stopping position it will strike the bar 215 and move that bar

downwardly, whereupon both of the levers 192 and 209 will be released and allowed to rock counter-clockwise under the tension of the spring 197, whereupon the spring 233 (Fig. 7) will rock the bell crank 230 clockwise, thus moving the link 234 to the right which in turn moves the link 238 to the right and closes the switch 144 after the carriage has settled in the position into which it was tabulated. If the position into which the carriage is tabulated happens to be the total columnar position, the stop 169 (Fig. 2) acts in the manner previously described, to withdraw the latch 187 from engagement with the notch 188 in the total key 75. In such position of the carriage, the block 147 closes switch 146, whereupon the electromagnet 149 is energized (assuming at this time that the switches 142, 143, and 145 were closed), to depress the total key 75. When the carriage is tabulated into the sub-total columnar position, then the stop 169 (Fig. 2) controls the lever 171 to withdraw the latch 187, and the block 148 closes the switch 146, in the manner described above.

Control of electromagnet by the overdraft or negative balance mechanism

In machines of this type, as shown by the patent to Lee, No. 2,079,355, it is impossible to depress the total key 75, or the sub-total key 76, when the totalized elements 70 are in a negative or overdrawn condition. When the totalizer elements are in negative condition, the overdraft key 77 is released, and it may then be depressed to take the negative balance from the totalizer elements 70. During a negative balance operation, the total key 75 remains locked by the latch finger 187 (Fig. 5). However, as has been previously stated, when the carriage is moved into the balance position, the latch finger 187 is withdrawn, thus freeing the total key 75, and therefore it is highly desirable and necessary that the circuit to the electromagnet 149 be broken when the totalizer elements 70 are in a negative or overdrawn condition.

This mechanism will now be described for breaking the circuit to the electromagnet 149 when the totalizer elements 70 are in a negative or overdrawn condition. As has been previously described, the link 79 (Fig. 1) is moved to the left to release the latch 78 from the key 77, to unlock this key for depression whenever the totalizer elements 70 are in a negative condition. Rigidly connected to this link 79 is an arm 260, which carries one blade of the previously mentioned switch 143, which is normally closed. By referring to Fig. 1, it can be seen that, whenever the link 79 is moved to the left, due to an overdraft condition of the totalizer element 70, to unlock the overdraft key, the arm 260 will be moved toward the left, thus opening the switch 143 and breaking the circuit to the electromagnet 149 so that, notwithstanding the fact that the carriage has been tabulated to the balance columnar position, the electromagnet 149 will not be energized, and consequently the total key 75 will not be automatically depressed whenever the totalizer elements are in a negative or overdrawn condition.

Control of electromagnet by machine operating mechanism during adding

It is also very desirable that the electromagnet 149 be not energized during any movement of the machine during adding operations or any other type of operation except the proper time

for taking a total or a sub-total from the totalizer. To accomplish this, the switch 143 (Fig. 1), which is normally closed, is adapted to be opened upon the initial movement of the operating mechanism to drive the machine. The operating arm 66 (Fig. 1) carries a stud 261 engaged by an arm 262, which is pivoted on the shaft 67. Pivoted to this arm 262 is a link 263, which is used in connection with special tabulating mechanism shown in the above-mentioned Christian Patent No. 2,082,098. This link 263 is adapted to be moved to the right upon the beginning of every operation of the machine by the motor link 65 in the manner previously described. Rigidly secured to the link 263 is an arm 264, which carries one of the blades of the switch 143, and consequently, whenever this link 263 is moved toward the right, the arm 264 opens the switch 143, thus breaking the circuit to the electromagnet 149 upon the initial movement of any operation of the machine. At the end of any machine operation, the link 263 is moved back to the position shown in Fig. 1, whereupon the switch 143 is again closed, so that, should the carriage be tabulated to the balance or sub-balance columnar positions and all of the other switches in circuits, as viewed in Fig. 4, be closed, then the electromagnet 149 can be energized upon the closing of the switch 145 to automatically depress the total key 75 or the sub-total key 76, as the case may be, as a preliminary to an operation of the machine to take the balance or the sub-balance.

Control of the electromagnet by the carriage return mechanism

It is also very desirable that the electromagnet 149 be not energized during the carriage return movement; in other words, during the time the carriage is being returned from any of its tabulated positions back to its normal position. Therefore the switch 145 (Figs. 4 and 10) is arranged in circuit with the electromagnet 149. This switch is normally closed, but immediately upon the beginning of the carriage return movement this switch 145 is opened to break the circuit to the electromagnet 149 to positively prevent any actuation of the electromagnet, thus preventing depression of the total key or the sub-total key during the carriage return movement. The switch 145 (Fig. 10) has one of its contact arms mounted on a block 266 secured to the carriage return head 132. The other contact of the switch 145 is carried by an arm 267, which is secured to the block 129, which, it will be recalled, is rocked in a counter-clockwise direction upon the movement of the lever 130, which is caused by the stop 121 (Fig. 9) on the carriage contacting the upturned finger of the bar 122, which initiates the carriage return movement. Consequently, when this block 129 is moved counter-clockwise, the arm 267 is raised, thus opening the switch 145 and breaking the circuit to the electromagnet 149 so that this magnet cannot be energized during any carriage return movement.

Typewriting mechanism and control of electromagnet by the same

In Fig. 6 there is shown a usual type bar 257 with its operating link 268, which, when the type bar is moved into position to type, contacts and operates an escapement frame 289 to operate an escapement pawl 270 (Fig. 7) and the retaining pawl 243, to cause the carriage 100 to

be letter-spaced by the ratchet wheel 244, the gear 246, and the rack 247.

For a more detailed description of the typewriting mechanism, reference may be had to the above-mentioned Ellis Patent No. 1,197,276 and also to the Ganger Patent No. 2,217,221, above referred to, which shows the complete typewriter escapement mechanism and how it is actuated.

It is desirable that the electromagnet 149 be not operated during the time the typewriting mechanism is being operated to type any notes or letters in connection with the accounting machine.

The blocks 147 and 148 (Fig. 10) are of sufficient length to cover three letter spaces of the typewriter escapement, and consequently, when the carriage is tabulated so that the block 147, for example, strikes the switch 146, it will close the switch and hold it closed for a distance of three letter spaces of the typewriter carriage 100. During this time, however, it is necessary that the total key 75 be not depressed. However, as soon as the first typewriter space of the block 147 contacts the switch 146, it will close the same and energize the electromagnet 149, which will immediately tend to pull down on the key 75 and cause the key 75 to hold the latch 187 so as to prevent movement or disengagement of this latch 187 from the key 75 at the time when the stop 168 or 169 arrives on top of the finger 170 of the lever 171. When this occurs and the electromagnet 149 is energized prior to that time, due to the length of the blocks 147 and 148, the spring 176 is merely stretched and the link 178 cannot be raised due to the pressure of the upper edge of the notch 188 of the total key 75 on the latch finger 187.

OPERATION

Since the operations of all of the parts of the various mechanisms have been fully described in connection with the detailed description thereof, it is believed that it is not necessary to go into any lengthy description of the operation of the entire machine other than to say that, when the accounting machine of the type herein disclosed and described is being used for bookkeeping, and the traveling carriage has been tabulated into a definite predetermined position, such as the total or balance column or the sub-total or sub-balance column, in which position stops 168 and 169, respectively, are in positions directly over the finger 170 of the hanging bar lever 171 to cause release of the latch 187 from the total key 75, the switch 146, which is normally opened, is closed by the block 147 on the traveling carriage, thus energizing the electromagnet 149, whereupon it automatically depresses the total key 75. This operation of the electromagnet 149, of course, depends upon whether or not the other four switches (Fig. 4) 142, 143, 144, and 145, in series circuit with the electromagnet 149, are closed.

The snap switch 142, of course, is the first one to be closed by the operator, and the switch 143 will remain closed provided there is no overdraft or negative balanced in the totalizer elements 70, and also provided that the operating mechanism, consisting of the arm 66 and the shaft 67, driven by the link 65 from the motor, is in its normal position. Likewise the switch 144 must also be closed, and this switch will remain closed if the tabulating mechanism is not in operation, as has been described previously. The switch 145 (Fig. 10) must also be closed, which will be the case

if the carriage return mechanism is not in operation. In taking sub-totals, of course, the subtotal key 76 is held by its latch (not shown after being depressed by the bell crank 111 (Figs. 6 and 8), at which time the block 148 (Fig. 10) is the activating means for closing the switch 146.

While the form of mechanism herein shown and described is admirably adapted to fulfill the objects primarily stated, it is to be understood that it is not intended to confine the invention to the form of embodiment herein disclosed, for it is susceptible of embodiment in various forms all coming within the scope of the claims which follow.

What is claimed is:

1. In a machine of the class described, the combination of an accumulator; a manually depressible total key for conditioning certain elements of the machine for total operations; means for operating the machine to add into, or subtract from, the accumulator and to take totals therefrom; a traveling carriage; electromagnetic means for depressing the total key; means operated by the carriage for rendering the electromagnetic means effective; a manually depressible, normally locked overdraft key; means controlled by the accumulator for unlocking the overdraft key; and means intermediate said overdraft key and said machine operating means and operable by the overdraft key unlocking means upon operation of the same to prevent operation of said electromagnetic means, said intermediate means being operable by said machine operating means during adding operations.

2. In a machine of the class described, the combination of typewriting mechanism; an accumulator; a manually depressible total key for conditioning certain elements of the machine for total-taking operations; carriage tabulating mechanism; a traveling carriage adapted for letter space movement under control of the typewriting mechanism and adapted for column space movement under control of the tabulating mechanism; a total key locking device for normally preventing depression of said total key; means on the traveling carriage for releasing the locking device from the total key when the carriage is in a certain position; and electromagnetic means for depressing the total key when said carriage has been moved into said certain position by the tabulating mechanism, and for preventing release of the locking device from the total key when the carriage has been moved into said certain position by the typewriting mechanism, to prevent depression of the total key during typewriting.

3. In a machine of the class described having a traveling carriage adapted for letter space movement and for column selecting movement under control of typewriting mechanism and tabulating mechanism respectively; in combination with an accumulator; a manually depressible total key for conditioning certain elements of the machine for total-taking operations; a locking device normally

engaging said total key to prevent depression thereof; means on the traveling carriage for releasing the locking device from the total key when the carriage is in a predetermined position; and means under control of the tabulating mechanism for depression the total key when said carriage has been moved into said predetermined position by the tabulating mechanism, and under control of the carriage for preventing release of the locking device from the total key when said carriage has been moved into said predetermined position by the typewriting mechanism.

4. In a machine of the class described having a traveling carriage adapted for letter space movement and for column selecting movement under control of typewriting mechanism and tabulating mechanism respectively; in combination with an accumulator; a manually depressible total key for conditioning certain elements of the machine for total-taking operations; a locking device normally engaging said total key to prevent depression thereof; means on the traveling carriage for releasing the locking device from the total key when the carriage is in a predetermined position; electromagnetic means for depressing said total key when the carriage is in said predetermined position but normally de-energized; a normally open switch in circuit with the electromagnetic means; a second normally closed switch in circuit with said electromagnetic means; a device on the carriage for closing said open switch as the carriage approaches said predetermined position to cause the electromagnetic means to prevent release of the locking device from the total key; and means controlled by the tabulating mechanism to open said second switch during tabulating movement of the carriage and hold said switch open until the carriage has stopped in said predetermined position, then releasing said opened second switch to complete the circuit to energize the electromagnet to cause the latter to depress the total key.
